CIGARETTE AND CIGAR QUENCHER

William E. Hummel, Santa Barbara, Calif.

Application May 18, 1939, Serial No. 274,457

4 Claims. (Cl. 131—236)

This invention relates to improvements in cigarette and cigar quenchers, its foremost purpose being to provide a device of this character which will work in an effective and clean manner. It is common knowledge that ash trays are currently used as cigarette snuffers, the result in many instances being the spreading of a disagreeable odor from cigarette and cigar butts which have been incompletely extinguished.

It is also a common experience that the currently used ash tray does not always serve the intended purpose of keeping the ashes in one place. It is quite easy for the ashes to blow out and thus defeat one of the purposes for which the tray is intended. Again, an open ash tray does not always insure immunity from a fire hazard. With this premise in mind the objects of the invention are as follows:

First, to provide a cigarette and cigar quencher which has a high safety factor from the standpoint of making sure to quench the fire, the ashes being retained at the same time and thereby affording an appliance which is a contribution toward cleanliness in the smoker's habits.

Second, to provide a quencher of the foregoing character in which a small pump is adapted for use in periodically filling a basin in the removable cover of a water reservoir, said basin and pump being virtually integral parts of said cover, so that the removal of the cover permits free access to both main parts of the device.

Third, to provide a quencher wherein the water supply and the quenching water are kept separate, the former being held in a container from which small quantities of water are pumped from time to time into a basin forming a part of the container cover.

Fourth, to provide a quencher wherein the ashes are confined to the quenching basin which is separate and apart from the water in said reservoir, to which basin the ashes are confined so as not to be mixed with the water in said reservoir.

Other objects and advantages will appear in the following specification, reference being had to the accompanying drawing, in which:

Figure 1 is a perspective view of the improved quencher.

Figure 2 is a central vertical section.

Figure 3 is a plan view of the quencher.

Figure 4 is a cross section taken on the line 4—4 of Fig. 2.

Figure 5 is a detail perspective view of the basin lid, and

Figure 6 is a detail perspective view of a valve hereinafter described.

The quencher is generally designated 1. As plainly shown in Fig. 2 it comprises a container or reservoir 2 which, in practice, may be made as large or small as desired. It is also within the purview of the invention to ornament the reservoir as the fancy of the manufacturer may dictate so as to provide an attractive smoker's accessory.

As shown in Fig. 2 the reservoir 2 contains a volume of water 3. The water is replenished from time to time by taking off the cover 4 and pouring the water in. This cover is flanged so as to fit down tightly around the rim of the reservoir, but not so tightly that difficulty will be experienced with its removal. The joint which the flange affords is, nevertheless, sufficiently good to prevent leakage of the water in the event that the quencher is tipped over, it being necessary, however, to stand the latter up again promptly because the joint in question is not water-tight.

A cavity 5 is formed in the cover 4. This cavity is herein known as the basin. It is in off-centered relationship to the cover 4 (Fig. 3), thereby providing what is conveniently termed a plunger space 6.

A rim 7 is affixed to the cover 4 around the basin 5 in upstanding relationship. This rim in effect increases the available depth of the basin, although ordinarily the level of water in the basin does not have to go higher than the surface of the cover 4.

A lid 8 has a flange 9 which fits down inside of the rim 7. This is a fairly tight fit, and it is capable of also preventing the leakage of water from the basin in the event of the quencher being tipped over. The lid includes a dished portion 10. This has a central hole 11 which provides a scraping edge 12. The cigarette or cigar is introduced into the dished part of the lid whereupon the ashes are struck off at the scraping edge 12 and fall into the water in the basin where the fire is quenched. A pump 13 is used to replenish the basin 5 from time to time. The basin contains only a small amount of water, and when this is absorbed by the ashes it will be necessary to pump a fresh quantity. The pump depends from the cover 4, and comes off of the quencher with the cover.

Said pump comprises a barrel 14 which is internally threaded at each of its ends as at 15, 16. The internally threaded portion 15 is screwed onto a nipple 17 which comprises an extension of a boss 18. Said boss is part of the cover 4, and

it has a duct 19 which provides communication between the basin 5 and the bore 20 of the nipple.

A valve 21 is carried by the barrel 14. It comprises a cage 22 which is screwed into the threaded end 16, the inner edge of an opening 23 in the cage providing a seat for the ball 24. The latter is loosely retained by a plurality of wires 25. The cage 22 provides an abutment for one end of a spring 26 inside of the barrel.

The other end of the foregoing spring presses against a plunger 27, tending to drive the plunger upwardly in the barrel. The plunger includes a cup leather 28, the rim of which is flexible enough to contract and thus recede from the wall of the barrel 14 on each downstroke, thus to bypass the water in the barrel to be lifted subsequently by the action of the spring. At that time the rim of the cup leather expands into engagement with the wall of the barrel, thus effecting the lifting action mentioned.

A stem 29 carries the plunger 27. It is guided by a packing gland 30 in the boss 18 and has a button 31 on its exposed end. It will be observed in Figs. 2 and 3 that the plunger stem 29 is situated in the previously mentioned plunger space 6. The latter affords adequate room for the downward depression of the button 20, without danger of the latter conflicting with the adjacent rim 7.

The operation

is readily understood. A few depressions of the button 31 and corresponding reciprocations of the plunger 27 will fill the basin 5 with a small amount of water from the reservoir 2. When the lighted end of a cigarette or cigar is introduced at the opening 11, the glowing ashes can be struck off at the scraping edge 12. When the basin becomes filled with ashes it is an easy matter to insert one's finger in the hole 11 and thereby pull the lid 8 out.

The dished formation 10 provides excellent insurance against scattering of the ashes either by blowing in or by the turning over of the quencher. The latter is capable of use virtually anywhere. It is adaptable to motor vehicles of all kinds as well as to use in the home and office. The dished formation 10 also provides a water deflector. It is situated more or less directly over the outlet of the duct 19.

Said duct stands on an incline, and being pitched as it is the water will be directed exactly against the inside of the dished formation 10 which then deflects the water downwardly into the basin 5. In other words, the operation of the pump will not result in discharging the water

from the quencher; to the contrary it is directed into the basin 5, as desired.

I claim:

1. A quencher comprising a water reservoir, a cover for the reservoir having a level top surface, a basin embodied in the cover, being sunk below said surface and being in off-centered relationship thereto so as to define a plunger space on one side of the basin, a pump depending from the cover within the area of said space into proximity to the bottom of the reservoir and having a plunger rod operable in and through said plunger space, said pump having a discharge opening directed on an incline into the basin, and a dished ash scraper surmounting the basin, being in line with the orifice of said opening to act as a water deflector.

2. A quencher comprising a water reservoir, a cover for the reservoir having a concavity in off-centered relationship thereto and providing a water basin, an upstanding rim around the basin defining a guard wall, the off-centering of said basin defining a plunger space, a pump depending from the cover, including a plunger rod operable in and through said plunger space and having a discharge opening at the inside of said rim, and a lid removably fitted on the rim, having a scraping edge in proximity to the basin and situated over the discharge opening to deflect the water into the basin.

3. A water reservoir having a cover with a basin, a boss depending from the cover and having a duct providing communication between the basin and the interior of the boss, a barrel carried by the boss and having a valve in its end farthest from the boss, a plunger operable in the barrel having a stem extending up through the boss for manual operation in one direction, and a spring tending to resist said operation and automatically moving the plunger in the opposite direction, said plunger including a cup leather having a rim adapted to flex inwardly of the barrel upon a stroke of the plunger in one of said directions.

4. A quencher comprising a water reservoir, a cover fitted on top of the reservoir to close it, said cover having a basin depending therefrom into the confines of the reservoir, a pump also depending from the cover into the confines of the reservoir and into the water therein, being operable to lift the water against gravity into the elevated basin, and back check means through which the water is required to be lifted, serving to prevent an inadvertent return passage of the water from the basin into the reservoir and thus avoid the contamination of the reservoir water.

WILLIAM E. HUMMEL.
